Primary Examiner — Jasmine Mlinarcik(74) *Attorney, Agent, or Firm* — Banner & Witcoff, Ltd.(57) **CLAIM**

The ornamental design for shorts, as shown and described.

DESCRIPTION

FIG. 1 is a front perspective view of shorts showing our new design;

FIG. 2 is a front view thereof;

FIG. 3 is a rear view thereof;

FIG. 4 is a left side view thereof;

FIG. 5 is a right side view thereof; and,

FIG. 6 is a rear perspective view thereof.

The shading represents contour only and no specific surface ornamentation is hereby claimed. The broken lines and the unshaded regions depicting the remainder of the shorts show features that form no part of the claimed design.
